CARBURETOR

Thorwald Brodersen, Park Ridge, and William C. Dunn, Chicago, Ill.

Application April 4, 1934, Serial No. 718,894

23 Claims. (Cl. 261—34)

This invention relates to improvements in carburetors for internal combustion engines, and has for one of its objects improved means for creating and maintaining the most desirable mixture proportion for the varying demands of the engine to which the device is connected.

In carburetors where the feeding of the fuel is due to aspiration or engine suction, considerable difficulty is sometimes experienced in starting the engine in very cold temperatures by reason of the inability of the engine to pick up the fuel and carry it into the cylinder. Such difficulty occurs by reason of stiffness of motor due to excessive friction created by congealed oil and also the condition of the gas in extreme cold. Furthermore due to the slowness of the rotation of the motor when attempting to start, due to congealed oil, or weak battery resulting from a hard starting motor, there is a lack of proper velocity of the air over the fuel jet, and it has heretofore been attempted to overcome these difficulties by forcing the fuel directly into the manifold and cylinder.

It is one of the objects of the present invention to provide in a carburetor of this character, improved means whereby a high velocity of air is obtained across the fuel jets when starting the motor under any condition, so that there will be a complete vaporization of the gas at the fuel jet openings regardless of the rate of speed of the motor when starting, and to also provide improved choking means by the use of which it is possible to cut off the auxiliary air supply and open wide the fuel feeding jets or nozzles, and force the fuel into a stream of high velocity primary air, with the result that the fuel will be thoroughly atomized so that it will be readily drawn or aspirated into the engine cylinder.

It is a further object of the present invention to provide improved means for automatically delivering to the engine a uniform and lean mixture over the complete range of speed when operating under a light load, and a slightly richer mixture over its complete range of speed when operating under a heavy load, and improved means whereby the fuel mixture will be automatically and readily changed when the load or requirements of the engine is changed, regardless of the position of the throttle valve, with the result that it is possible to acquire the greatest economy when the engine is not required to furnish the maximum power when the engine is operating under its heavy load.

A further object is to provide improved means for holding open an auxiliary fuel supply for sup-

plying fuel to the supply nozzle in choking or starting the engine.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a vertical, longitudinal sectional view of a carburetor of this character constructed in accordance with the principles of this invention.

Figure 2 is a view similar to Figure 1, on a smaller scale, and with parts omitted, and showing some of the parts in the position they will assume when engine suction is operating upon the piston valve to unseat the latter.

Figure 3 is an enlarged detail sectional view of the fuel metering valve.

Figure 4 is a view similar to Figure 1, showing the parts in the position which they assume when the choke is being operated and with the throttle about one-third open.

Figure 5 is a detail sectional view as taken on line 5—5, Figure 7.

Figure 6 is a sectional view taken on line 6—6, Figure 1, with parts omitted.

Figure 6a is a detail sectional view on line 6a—6a, Figure 4.

Figure 7 is a horizontal sectional view taken on line 7—7, Figure 1, with parts omitted.

Figure 8 is a sectional view taken on line 8—8, Figure 6, with parts omitted.

Figure 9 is an enlarged detail sectional view of the metering valve and a supplemental control valve for the fuel supply to the nozzle.

Figure 10 is a vertical, sectional view as taken on line 10—10, Figure 6.

Figure 11 is an enlarged detail view, partly in elevation, partly in section and showing the parts separated, of the piston valve and the means for controlling the metering valve.

Figure 12 is a detail sectional view taken on line 12—12, Figure 11.

Figure 13 is an enlarged sectional view of a detail.

Figure 14 is a detail sectional view, similar to Figure 6, of a modified form of the invention and with parts omitted.

Figure 15 is a detail sectional view taken on line 15—15, Figure 14.

Figure 16 is a detail sectional view taken on line 16—16, Figure 14.

Figure 17 is a sectional view taken on line 17—11, Figure 14.

Figure 18 is a detail sectional view taken on line 18—18, Figure 17.

Figure 19 is a detail sectional view taken on line 19—19, Figure 17.

Referring more particularly to the drawings, the numeral 15 designates a casing having an open chamber 16 in the top thereof closed by a cap member 17 within which latter is arranged a throttle valve 18. This cap member is provided with a flange 19 having threaded openings 20 by means of which the carburetor may be secured in position.

The cap member 17 is removably secured to the top of the casing by means of screws 21, for a purpose to be hereinafter described.

The casing 15 is provided with an air inlet opening 22 which communicates with the chamber 16, in a manner to be set forth, and within the chamber 16 is arranged a throat tube 23 of an external diameter considerably less than the internal diameter of the chamber 16, and the throat tube is supported in an opening in the top member 24 of a chamber 25, the tube being preferably of an external diameter considerably less than the diameter of the chamber 16, and below the chamber 25 is arranged another chamber 26.

The interior of the throat tube 23 is preferably bell shaped as shown in Figure 1, curving inwardly toward a central opening 27 through the bottom thereof, and the throat tube may be of any desired length, the same being fixedly secured in position.

A nozzle member 28 extends through an opening 29 in the bottom of the chamber 25 and forms a closure for such opening, the nozzle being secured in position by means of suitable fastening devices 30, in the form of screws. The nozzle extends through the chamber 25 and is provided with a conical upper end 31, which projects into the opening 27 in the bottom of the throat tube, and the exterior diameter of the nozzle 28 is considerably less than the internal diameter of the chamber 25.

Openings 32 (see particularly Figures 1 and 7) are provided in the wall 24 between the chambers 16 and 25, and these openings 32 may be of any desired length and form communicating passages between the chamber 25 and the portion of the chamber 16 in which the throat tube 23 is arranged.

The nozzle 28 is provided with a central passage 33 opening through the bottom thereof, extending lengthwise of the nozzle and terminating short of the apex of the conical end. Branch passages 34 lead from the passage 33 and project through the conical surface of the end of the nozzle and the passages 34 are arranged at substantially right angles to the conical surface of the nozzle.

Channels 35 are provided in the conical surface of the nozzle 28, and these passages 35 terminate at substantially the lower edge of the opening 27 of the throat tube 23, and the passages 34 in the nozzle communicate with and discharge into the channels 35, so that when air currents flow through the channels 35, in a manner to be described and into the throat tube 23, they will flow across the passages 34 and due to their high velocity will entrain or atomize fuel from the passages 34 into the throat tube 23.

The passage 33 in the nozzle is enlarged at its lower end as at 36 and such enlarged portion ex-

tends through the bottom of the nozzle. Within this enlarged portion are arranged valve members 37—38, the member 37 being provided with a tapering opening 39 therethrough and extending through the top of the valve member, while the member 38 is provided with an opening 40 therethrough, tapering in the opposite direction from the opening 39. The tapered opening of the valve member 37 forms an annular valve seat 41, while the tapered portion 40 of the valve member 38 forms an annular valve seat 42, and the diameter of the valve seat 42 is less than the diameter of the valve seat 41. These valve members 37—38 are superposed and are held in position by means of screws 43.

The proximate faces of the valve members 37 and 38 are provided respectively with openings 44—45 and the valve members are preferably cut away as at 46 to form a chamber with which the passages 44—45 communicate. Portions of the peripheries of the valve members 37—38 are also cut away so as to form an annular chamber 47, for a purpose to be hereinafter described.

A metering valve 48 co-operates with the valve seats 41 and 42 and this valve increases in diameter from both of the extremities 49—50 to the point 51 of its maximum diameter, which latter is disposed in proximity to, but is spaced for a substantial distance from the extremity 50, and the valve is of such a shape that portions thereof will co-operate with the respective seats 41—42 to control the passage of the fuel through the openings 40—39, as will be hereinafter described.

The metering valve 48 may be of any desired length and is supported by means of a disc or member 52 which is movable in the chamber 26, and the member 52 is supported by means of rods 53—54 that extend respectively through openings 55—56 in the wall of the chamber 25. The upper extremities of the rods 53—54 are secured to a piston valve 57 that moves within the chamber 16. This valve 57 is provided with an opening 58 therethrough and which opening communicates with the chamber 16 as well as with the opening in the throat tube 23.

A sleeve 59 surrounds the throat tube 23 and is slidable thereupon. The wall of the sleeve 59 increases in diameter at the upper end thereof as at 60, and the upper end of the sleeve is provided with a flared opening 61. The sleeve is of a length to project for any desired distance above the top of the throat tube 23 and is adapted to be moved upon and lengthwise of the throat tube, preferably by means of a rock shaft 62 (see particularly Figures 5 and 7) which is journaled in suitable bearings, and to the rock shaft is secured a yoke 63, the arms 64 of which are bifurcated as at 65 to receive lugs or projections 66 that extend from opposite sides of the sleeve 59. A lip or projection 67 extends from the yoke 63 and is so positioned that it will be engaged by an adjusting screw 68 threaded into the casing and by means of which adjusting screw the extent of movement of the sleeve 59 in one direction may be varied. It will be manifest that by adjusting the screw 68 the movement of the rock shaft 62 for controlling the longitudinal movement of the sleeve 59 may be varied and thereby cause the upper surface 69 of the sleeve 59 to be raised or lowered with respect to the top of the throat tube 23.

With this surface 69 (see Figure 1) the piston valve 57 co-operates and when the piston valve 57 is in the position shown in Figure 1, any air entering the passage 22 will be cut off from direct

flow into the chamber 16 between the seat 69 and valve 57 and through the opening 58, but will flow through the openings 32 and through the channels 35 across the fuel jet openings 34 and through the throat tube 23 and opening 58 into the chamber 16.

When the piston valve 57 is in the position shown in Figure 2 with respect to the seat 69 on the sleeve 59, air entering the passage 22 will flow into the chamber 16 through the opening between the piston valve 57 and the seat 69 and through the opening 58. At the same time some of the air will also pass through the openings 32 and thence into the channels 35 across the fuel jet openings 34 and thence through the throat tube 23 and through the opening 58 in the valve 57.

Encompassing the lower portion of the casing is a bowl 70 which is provided with a chamber 71 formed preferably by depressing a portion of the bottom of the wall of the bowl and which chamber or depression 71 is disposed beneath the disc or member 52. A cleanout opening 72 having a closure plug 73 being provided in the bottom of the chamber 71.

Within the bowl 70 is arranged a float 74 which controls a valve 75, the latter controlling the supply of fuel to the bowl 70 through the opening 76, a strainer 77 being provided over the opening 78 which is controlled by the valve 75.

The chamber 71 has communication with the bowl 70 by means of a passage 79 (see particularly Figure 1) and the top of the passage 79 is disposed below the top of the disc or member 52 when the latter is in its lowermost position, and the duty of the opening 79 is to feed the fuel below the disc 52 to break or overcome any vacuum which might be caused in the chamber 71 when the disc or member 52 is raised by the upward movement of the piston valve 57.

When the disc or member 52 is lowered the fuel will also pass through the opening between the periphery of the disc 52 and the wall of the chamber 26. This opening or space is controlled by means of a ring 80 (see particularly Figures 1, 11, and 13) which surrounds the reduced portion 81 of the disc 52 and is normally seated upon the face or shoulder 82, and the ring is free to move upon the disc, being held in position by means of collars 83-84 which respectively surround the rods 54-53. The ring 80 is of an internal diameter slightly larger than the diameter of the reduced portion of the disc 52 so as to form a passage therebetween, the ring being maintained in position by being disposed between the portion of the disc 52 beyond the reduced portion thereof and the collars 83-84. When the disc 52 is lowered the ring 80 will move upwardly, allowing the passage of fluid between the inner periphery of the ring and the periphery of the reduced portion of the disc 52, but when the disc 52 is raised, the ring will be seated to close the passage between the inner periphery thereof and the periphery of the reduced portion of the disc. The rod 53 is secured rigidly to the disc 52, the collar 84 encompassing a reduced portion 85 on the rod 53 so as to abut the shoulder 86 and rest against the upper surface of the disc. The reduced portion of the rod 53 passes through the disc and is secured by means of a nut 87 on the end of the reduced portion. The upper extremity of the rod 53 is reduced as at 88 and is provided with a threaded portion 89, and the reduced portion 88 passes through a collar 90 having a flange 91 which rests upon the top of the piston valve 57,

the collar passing through the piston valve to abut a washer 92 that rests against the shoulder 93 of the rod. A nut 94 is threaded upon the extremity of the reduced portion 88, and a washer 95 may be provided between the nut 94 and the flange 91 of the collar.

The other rod 54 is loosely secured to the disc 52 by means of the portion 96 of the collar 83 passing through an opening 97 in the disc and the external diameter of the collar is slightly less than the diameter of the opening. The reduced end 98 of the rod 54 passes through the collar 96 with the shouldered portion 99 abutting the end of the collar 83, and a nut 100 is threaded upon the end of the reduced portion 98. Likewise, the upper end of the rod 54 is reduced as at 101 to form a shoulder 102 which abuts a washer 103 that in turn abuts the end of the portion 104 of a collar 105. The portion 104 passes loosely through the piston valve 57 with a slight play therearound, and a nut 106 is threaded on the end of the portion 101 with the washer 107 between the nut and the collar 105.

With this construction it will be manifest that in the event the openings 55-56 in the casing are not properly positioned or not properly aligned with respect to the rods 53-54, the rod 54 may be rocked or positioned with respect to the disc 52 so that it will pass freely through the opening 56. Also the loose connection of the piston valve 57 with the rods 53-54 will permit the piston valve to move laterally so as to properly seat itself upon the surface 69, also to take care of any misalignment of the walls of the chamber 16 in respect to the rods 53 and 54.

The chamber 26 is provided with another opening 108 (see Figure 1) in the wall thereof, which communicates with the bowl 70, so that the fuel will flow through the opening 108 into the chamber 26 and from there will flow through the openings 41-42 past the valve 48, into the passage 33, to be discharged through the passages 34 into the channels 35 where it will be met by the air currents of high velocity and atomized into the chamber 16 through the throat tube 23 and opening 58 in the piston valve.

If desired, a valve 109 may be provided with and secured in position by means of a screw 110 which is adapted to be adjusted so as to vary the size of the opening 79.

In operation and assuming the parts to be in the position shown in Figure 1, and when the motor is starting, it will be seen that the piston valve 57 closes the direct communication between the passage 22 and the chamber 16, with the result that any air entering the passage 22 will flow through the openings 32 to enter the channels 35 to flow across the outlets 34 of the passage 33 and into the throat tube, atomizing the fuel. At the same time fuel from the bowl will be entrained or drawn up in the passage 33 and out of the passages 34 by the suction created in the chamber 16, the fuel flowing through the passages 41-42 around the metering valve 48.

As the engine suction increases the piston valve 57 will be raised to the position shown in Figure 2, and while being so raised will move off of the seat 69, thereby producing an opening through which some of the air currents entering the passage 22 will flow, and these air currents will pass through the opening 58 in the piston valve into the chamber 16 commingling with the air and fuel discharged through the throat tube 23.

Obviously, as the suction in the engine cylinder increases, the piston valve 57 will be raised.

to a greater extent and the adjustment of the metering valve 48 will be commensurate with the movement of the piston valve 57. The screws 43 which hold the valve seat members 37-38 in position will serve as stops to limit the upward movement of the disc 52 as well as the piston valve 57.

As the piston valve 57 rises the disc or member 52 will operate as a plunger, causing the fuel in the chamber 26 thereabove to be forced through the openings 41-42, passages 33-34 into the air channels 35, where it is met by the incoming air.

Some fuel will find its way out of opening 108, 15 but the volume of fuel above the disc member 52 is so great in chamber 26, that fuel will be forced by the disc 52 through the passages 33-34.

When the engine suction decreases the piston 20 valve, metering valve, and disc member 52 will fall by gravity, and the packing ring 80 will be moved off of its seat 82 so as not to retard the lowering movement of the disc or member 52.

With this construction it will be manifest that 25 the chamber 71 and the disc 52 operate as a dash pot to dampen or retard a too sudden movement of the piston valve 57 and metering valve 48 in either an opening or closing movement.

When the disc or member 52 is raised by the 30 movement of the piston valve 57, and due to the pressure exerted by the movement of the member 52 in the chamber 26, there would be a tendency for the fuel to flow through the openings 55-56 (see Figure 1) around the rods 53-54, 35 and unless provision is made to arrest such flow the fuel might flow through the openings into the air passage 22. In order to prevent this, openings 111 are provided through the wall of the chamber 25 which communicate with the 40 passages 55 and 56 and also with the interior of the bowl or tank 70.

With this construction it will be manifest that any fuel which might find its way through the 45 openings 55-56 will flow through the openings 111 back into the bowl 70.

Any suitable means may be provided to raise the sleeve 59 from its normal position (as shown in Figure 1) to a choking position, such for instance as an arm 112 provided on the rock shaft 62 (see particularly Figure 10), a swivel member 113, secured to the end thereof, and to which member 113 a wire 114 is connected. The wire leads through a tubular member 115 to any convenient point on the dash board. A lip or projection 116 is secured to the arm 112 and this projection rests against a plunger 117 which is normally moved by means of a spring 118 in a direction to contact with the projection and operates to move the arm in a direction to rock the shaft 62 to return the sleeve 59 to its normal position. The wire 114 serves as a choke so that when it is desired to choke the engine and by pulling upon the wire, the arm 112 will be raised to cause the rock shaft 62 (see also Figure 4) to move in a direction that the sleeve 59 will assume the position shown in Figure 4. During this movement and as the end of the sleeve 59 contacts with the piston valve 57, the latter will be raised by the choking operation, and this in turn will raise the metering valve 48 to the position shown in Figure 4. At the same time and as the disc 52 rises the fuel will be forced thereby out of the passages 34 into the channels 35 to be met and

atomized by the high velocity of air flowing through the channels 35.

During the choking operation the sleeve 59 will be raised and this will correspondingly adjust the metering valve 48. However, after partial choking and when the engine is running, suction will be manifested upon the piston rod 57 to raise the same off of the seat 69, and at the same time the metering valve 48 will be further adjusted or opened with respect to the seat 41-42 10 to permit an augmented supply of fuel to the passages 33-34. Then the degree of richness of the fuel can be controlled by the driver.

As soon as the choking operation is completed and the wire 114 released, the spring 118 will 15 force the plunger 117 against the lip or projection 116 to rock the shaft 62 to return the sleeve to its normal position.

Under heavy loads it is desirable to have a rich 20 mixture and it is also desirable that when the engine is running free or on a light load, the mixture should be lighter. Therefore, in order to vary the mixture by increasing or decreasing its richness there is provided means for automatically controlling the same, and which means is 25 itself automatically controlled by engine suction. To that end there is provided a chamber 119 (see particularly Figures 8 and 9) in the wall of the casing, within which a plunger 120 operates. Communicating with the chamber 119 is a passage 121 which also has communication with the chamber 16, above the throttle valve 18.

The upper extremity of the piston 120 may be reduced or tapered as at 122, if desired. A control valve 123 operates in a casing 124, and which casing 124 has an opening 125 in the top thereof which communicates with the bowl or tank 70. The valve 123 has a conical extremity 126 which extends through the opening 125 and a spring 127 tends normally to seat the valve 126. Leading 40 from the valve casing 124 is a passage 129 which has communication with the passage 41 in the enlarged portion 36 of the passage 33, so that when the valve 126 is opened, fuel will flow through the opening 125 into the passage 129, and thence to 45 the passage 41, through the openings 44-45 in the valve seat members 37-38, to be discharged through the passage 41 into the passage 33, thereby augmenting the supply of fuel to be discharged through the passages 34. The passage 41 is a determined greater opening than the passage 42 and this greater opening is maintained on the entire travel of the metering valve 48.

The valve 126 is normally closed by the spring 127 and when the engine is running the suction 55 in the engine cylinder will cause the piston 120 to rise, and the suction will hold the piston in a position out of contact with the valve 126. When, however, the engine suction decreases, the piston 120 will fall, contacting with the valve 126 and 60 the weight of the piston 120 is sufficient to unseat the valve 126 against the stress of the spring 127, to permit the fuel to flow through the opening 125 into the passage 129.

When the engine suction increases again, such 65 suction will be manifested upon the piston 120, through the passage 121 and the piston will again be raised, permitting the spring 127 to move the valve 126 in a direction to close the opening 125.

Another means for raising the sleeve 59 so as 70 to raise the seat 69 and also adjusting the metering pin 48 to a fixed position, is shown in Figures 14 to 19, in which there may be provided a shaft 131 journaled in suitable bearings, with one end thereof projecting into the portion of the 75

chamber 16 in which the sleeve 59 is arranged. On the end of this shaft 131 is secured eccentrically a cam 132 which operates in a suitable bearing 133 secured to the sleeve. The other end of the shaft 131 projects for a distance beyond the bearing and has secured to it for movement therewith, in any suitable manner, such as by means of a portion of the shaft being angular in cross section, to form an angular bearing, an arm 134 by means of which the shaft 131 may be rotated in its bearing. Carried by the arm 134 is a pin or projection 135 adapted to enter sockets 136 in a fixed portion of the structure so as to maintain the shaft 131 as well as the eccentric cam 132 and the sleeve 59 in their adjusted positions.

Encompassing the end of the shaft 131 is a sleeve 137 secured thereto in any suitable manner, such as by means of a fastening pin 138. The sleeve is open at the inner end and is of a diameter considerably larger than the diameter of the adjacent portion of the shaft 131. A spring 139 encompasses the shaft with one end seated in the cap 137 and resting against the bottom wall thereof. The other end of the spring abuts the arm 134 and tends normally to move it in a direction to cause the pin or projection 135 to enter one of the recesses 136.

With this construction it will be manifest that when it is desired to adjust the sleeve 59 the arm 134 is moved longitudinally of the shaft 131 until the pin 135 is unseated from one of the recesses 136. When the arm is in this position, the shaft 131 may be rocked and when the arm 134 is released, the stress of the spring 139 will move the arm in a direction on the shaft 131 to cause the pin or projection 135 to enter one of the recesses 136.

It will thus be manifest that a fixed adjustment may be given to the sleeve 59.

In choking the engine, it may be desirable to hold the piston 57 down so that the air entering the passage 22 will not flow directly against the piston to raise the same, and in order to prevent the air from flowing directly from the passage through the opening 58 in the piston 57 and into the chamber 16, and to cause the air to take a downward course through the openings 32 and thence through the passages 35 across the fuel outlets 34.

In order to effect this, any suitable means may be provided, such for instance as a shaft 140 journaled in suitable bearings and having secured thereto for rotation therewith a cam 141. The shaft 140 and the cam 141 are so positioned that the cam may be brought into contact with the periphery of the piston 57, as seen more clearly in Figures 14 and 15, and this cam is adapted to be moved into binding engagement therewith by rocking the shaft 140, preferably through the medium of a rod 142 pivoted to the end of an arm 143, which in turn is secured as at 144 to the shaft 140. A spring 145 is anchored by one end as at 146 to a stationary part of the structure, and is secured at its other end as at 147 to the shaft 140. The normal tendency of the spring 145 is to raise the cam 141 to move the same out of engagement with the periphery of the piston 57 so as to permit the latter to have a free movement. When, however, the rod 142 is operated, the arm 134 will be raised and the cam 141 will be lowered against the stress of the spring 145, and this will frictionally hold the piston 57 against movement. As soon as the stress is re-

lieved upon the rod 142, the spring 145 will return the cam 141 to its normal position.

Obviously, the cam and the shaft will operate in a housing 148, where they will be protected.

At the same time that the piston 57 is held down, which will be in starting or choking, means are provided for holding down the piston 120 to hold the valve 123 down and thereby maintain the fuel passage 125, which communicates with the passage 129, open so as to permit fuel to enter the passage 129 for the purpose of supplying fuel to the nozzle 28 in starting.

This may be effected in the following manner.

When the engine suction is not sufficient to hold the piston 120 elevated, the piston will fall by gravity to the position shown in Figure 16. That is, so that the piston will engage the extremity of the valve 123 and depress the same against the stress of the spring 127, thereby opening the passage 125. When this piston 120 is in this position, which will occur when the piston 57 is in its lowermost position or in the position shown in Figure 15, the piston 120 is held against being raised by engine suction by another cam 149 secured also to the shaft 140. This cam 149 is so positioned that when it is lowered the periphery thereof will contact with the periphery of the piston 120 and will frictionally bind or hold the piston 120 against being raised by engine suction. These two pistons 57 and 120 may thus be held, locked, so to speak, against being raised by engine suction and when in this position, and the engine is started, a supply of fuel will be delivered to the nozzle until the engine starts to run. As soon as the engine starts to operate the pistons 57 and 120 may be released by releasing the strain upon the operating rod 142, and immediately the spring 145 will operate to turn the shaft 140 in a direction to raise the cams 141 and 149 so that they will be moved respectively out of contact with the peripheries of the pistons 57 and 120, after which the pistons 57 and 120 will operate in the manner as already described.

With the adjustment means for the sleeve 59 it will be manifest that the sleeve may be raised to any desired extent followed by the rising or adjustment of the metering pin 48, so that more fuel may be supplied while starting and at the same time there will be provided a permanent adjustment for these parts.

The cap member 17 may be provided with additional openings 130, similar to the opening 121, only one of which however is in communication with the chamber 119, and by being removably secured in position by the screws 21, it will be manifest that this cap member may be rotatably adjusted so as to permit the same to be adjusted to different designs of manifolds.

If desired, a baffle 57^a may be provided below the piston 57 and the upper face thereof is disposed below the lowest plane of the surface 69, so as not to interfere with the seating of the piston valve 67 against the surface 69. The function of said baffle is to deflect the air entering beneath the piston valve 57 toward the center of the opening 58, with the result that the velocity of the air will not operate or have a tendency to lift or drive the piston valve 57 towards the top of the chamber 16 by the momentum of the air currents.

While the preferred forms of the invention have been herein shown and described, it is to be understood that various changes may be made in the details of construction and in the combination and arrangement of the several parts, with-

in the scope of the claims, without departing from the spirit of this invention.

What is claimed as new is:—

1. In a carburetor, a fuel nozzle, means for supplying fuel to the nozzle, a metering valve for controlling the supply of fuel to the nozzle, an air supply passage for directing air across the nozzle to atomize the fuel therefrom, a fuel mixing chamber, a piston operating in said chamber above the nozzle and controlled in its operation by engine suction, and a connection between said piston and said metering valve whereby the operation of the valve will be controlled by the movement of said piston, the connection being disposed out of the path of movement of the fuel from the nozzle to the mixing chamber, all of the parts being entirely housed within the carburetor.
  2. In a carburetor, a fuel nozzle, means for supplying fuel to the nozzle, a metering valve for controlling the said supply, a mixing chamber, an air supply passage having direct communication with said chamber above the nozzle, means for directing a portion of the air from said passage across the nozzle to atomize the fuel therefrom into said chamber, a piston in the chamber above the nozzle and controlled in its operation by engine suction, and a connection between said piston and said valve whereby the operation of the valve will be responsive to the movement of the piston, said piston also serving as a valve to control the direct connection between the air passage and said chamber, the said connection between the piston and the said valve being disposed out of the path of movement of the fuel from the nozzle to the mixing chamber, all of the parts being housed within the carburetor.
  3. In a carburetor, a fuel nozzle, means for supplying fuel to the nozzle, a metering valve for controlling the said supply, a mixing chamber, an air supply passage having direct communication with said chamber above the nozzle, means for directing a portion of the air from said passage across the nozzle to atomize the fuel therefrom into said chamber, a piston in the chamber above the nozzle and controlled in its operation by engine suction, a connection between said piston and said valve out of the path of movement of the fuel from the nozzle to the mixing chamber whereby the operation of the valve will be responsive to the movement of the piston, said piston also serving as a valve to control the direct connection between the air passage and said chamber, and a plunger also responsive in its operation to the movement of said piston for forcing fuel through said nozzle.
  4. In a carburetor, a fuel nozzle, means for supplying fuel to the nozzle, a metering valve for controlling the supply of fuel to the nozzle, an air supply passage for directing air across the nozzle to atomize the fuel therefrom, a fuel mixing chamber, a piston operating in said chamber above said nozzle and controlled in its operation by engine suction, a connection between said piston and said metering valve below the latter whereby the operation of the valve will be controlled by the movement of said piston, and means independent of the said piston and remote from the valve and also responsive in its operation to engine suction and operating to augment the supply of fuel to the nozzle past said metering valve.
  5. In a carburetor, a fuel nozzle, means for supplying fuel to the nozzle, a metering valve for controlling the supply of fuel to the nozzle, an air supply passage for directing air across the nozzle to atomize the fuel therefrom, a fuel mix-
- ing chamber, a piston operating in said chamber above the nozzle and controlled in its operation by engine suction, a connection between said piston and said metering valve whereby the operation of the valve will be controlled by the movement of said piston, means also responsive in its operation to engine suction and operating to augment the supply of fuel to the nozzle past said metering valve, the last recited means embodying a passage having communication with the fuel supply and said nozzle, a valve for the last said passage, means tending normally to move the valve in a direction to close the passage, and a member reciprocable under the influence of engine suction and adapted when the engine suction drops, to actuate the last said valve against the stress of the valve closing means to open the last said passage.
6. In a carburetor, a fuel supply nozzle, means for supplying fuel thereto, a mixing chamber, an air passage having direct communication with said chamber above and remote from the nozzle, said air passage also leading across the nozzle to atomize fuel from the nozzle into said chamber, means spaced above and substantially concentric with the nozzle and influenced by engine suction for opening and closing the said direct communication between the air passage and said chamber, a metering valve for metering the fuel through the nozzle, and an operative connection between the last said means and the said metering valve and out of the path of the fuel discharged from said nozzle whereby the operation of the metering valve will be responsive to the movement of the former, all of the parts being entirely housed within the carburetor.
7. In a carburetor, a fuel supply nozzle, means for supplying fuel thereto, a mixing chamber, an air passage having direct communication with said chamber and remote from the nozzle, said air passage also leading across the nozzle to atomize fuel from the nozzle into said chamber, means disposed above and in alignment with the nozzle and influenced by engine suction for opening and closing the said direct communication between the air passage and said chamber, a metering valve for metering the fuel through the nozzle, an operative connection between the last said means and the said metering valve housed within the carburetor and disposed out of the path of movement of the fuel from the nozzle to the mixing chamber, whereby the operation of the latter will be responsive to the movement of the former, means embodying a valved passage having communication with the fuel supply and the nozzle for augmenting the supply of fuel to the nozzle past said metering valve, and means influenced by engine suction for actuating the last said valve to open the last said passage.
8. In a carburetor, a fuel supply nozzle, means for supplying fuel thereto, a mixing chamber, an air passage having direct communication with said chamber and remote from the nozzle, said air passage also leading across the nozzle to atomize fuel from the nozzle into said chamber, means disposed above and concentric with the nozzle and influenced by engine suction for opening and closing the said direct communication between the air passage and said chamber, a metering valve for metering the fuel through the nozzle, an operative connection between the last said means and the said metering valve whereby the operation of the latter will be responsive to the movement of the former, a valved passage having communication with the fuel

supply and the nozzle for augmenting the supply of fuel to the nozzle past said metering valve, a cylinder, a piston movable in said cylinder under the influence of engine suction, said piston operating when engine suction drops, to open the valve in the last said passage, and means for subsequently closing the last said valve.

9. In a carburetor, a fuel nozzle, means embodying a metering valve for supplying fuel to the nozzle, an unobstructed and open throat tube into which the nozzle discharges, a mixing chamber with which the throat tube communicates, an air passage having communication with said chamber and also leading across said nozzle, a piston in the chamber spaced above and concentric with the throat tube and influenced in its movement by engine suction, said piston having an opening therethrough in alignment with the end of the throat tube, a plunger with which the piston is connected for forcing fuel into said nozzle, and an operative connection between said plunger and said metering valve for operating the latter, said connection being disposed out of the path of the fuel discharged from the said nozzle, said piston operating to control the communication between the said chamber and the air passage, all of the parts being housed within the carburetor.

10. In a carburetor, a fuel nozzle, means embodying a metering valve for supplying fuel to the nozzle, a throat tube into which the nozzle discharges, a mixing chamber with which the throat tube communicates, an air passage having communication with said chamber and also leading across said nozzle, a piston in the chamber above and concentric with the throat tube and influenced in its movement by engine suction, a plunger below the nozzle, with which the piston is connected for forcing fuel into said nozzle, an operative connection between said plunger and said metering valve for operating the latter, the last said connection being disposed out of the path of the flow of the fuel from the nozzle to the mixing chamber, said piston operating to control the communication between the said chamber and the air passage, said nozzle being disposed between the piston and said plunger, and means whereby fuel may be supplied on both sides of said plunger.

11. In a carburetor a mixing chamber, an open ended upright throat tube in said chamber, a fuel nozzle discharging into one end of said tube, means for supplying fuel to the nozzle, an air passage having direct communication with said chamber over the top of said tube, said passage also leading across the end of said nozzle, a sleeve slidable upon and longitudinally of said tube, the upper end of said sleeve forming a valve seat at the top of said tube, a piston movable in said chamber under the influence of engine suction and adapted to co-operate with said valve seat to control the direct communicating passage between the air passage and said chamber, means whereby the movement of the piston will control the supply of fuel to the nozzle, and means for moving said sleeve lengthwise of said tube to vary the position of said valve seat with respect to the end of said tube, and while the parts of the carburetor remain intact.

12. In a carburetor a mixing chamber, an open ended upright throat tube in said chamber, a fuel nozzle discharging into one end of said tube, means for supplying fuel to the nozzle, an air passage having direct communication with said

chamber over the top of said tube, said passage also leading across the end of said nozzle, a sleeve slidable upon and longitudinally of said tube, the upper end of said sleeve forming a valve seat at the top of said tube, a piston movable in said chamber above the throat tube, under the influence of engine suction and adapted to co-operate with said valve seat to control the direct communicating passage between the air passage and said chamber, means whereby the movement of the piston will control the supply of fuel to the nozzle, means for moving said sleeve lengthwise of said tube to vary the position of said valve seat with respect to the end of said tube and while the parts of the carburetor remain intact, and means operatively connected with said piston for forcing fuel into said nozzle upon the movement of the piston.

13. In a carburetor a mixing chamber, an open ended throat tube in said chamber, a fuel nozzle discharging into one end of said tube, means for supplying fuel to the nozzle, an air passage having direct communication with said chamber over the top of said tube, said passage also leading across the end of said nozzle, a sleeve slidable upon and longitudinally of said tube, the end of said sleeve forming a valve seat at the top of said tube, a piston movable in said chamber under the influence of engine suction and adapted to co-operate with said valve seat to control the direct communicating passage between the air passage and said chamber, means whereby the movement of the piston will control the supply of fuel to the nozzle, means for moving said sleeve lengthwise of said tube to vary the position of said valve seat with respect to the end of said tube, means operatively connected with the piston for forcing fuel into said nozzle, means for augmenting the supply of fuel to the nozzle, and means also responsive in its action to engine suction for controlling the said augmenting supply of fuel to the nozzle.

14. In a carburetor, a fuel supply nozzle, a mixing chamber into which the nozzle discharges, a metering valve for controlling the supply of fuel to the nozzle, a fuel supply chamber below the nozzle, a plunger in the last said chamber, said plunger operating to actuate said valve, a piston above the nozzle and responsive in its operation to engine suction, rods connecting the plunger and piston, said rods passing through bearings which communicate with said fuel supply chamber, and means comprising passages communicating with and leading from said bearings for discharging from said bearings fuel which may be drawn thereinto.

15. In a carburetor, a fuel supply nozzle, a mixing chamber into which the nozzle discharges, a metering valve for controlling the supply of fuel to the nozzle, a fuel supply chamber below the nozzle, a plunger in the last said chamber, said plunger operating to actuate said valve, a piston above the nozzle and responsive in its operation to engine suction, rods connecting the plunger and piston, said rods passing through bearings which communicate with said fuel supply chamber, means comprising passages communicating with and leading from said bearings for discharging from said bearings fuel which may be drawn thereinto, and a loose packing ring encompassing said plunger, said ring operating to permit passage of fuel past said plunger in one direction and preventing passage of the fuel past the plunger in the opposite direction.

16. In a carburetor a structure embodying a

fuel nozzle, a piston above and a plunger below and spaced from the nozzle, and rods connecting the piston and plunger, one of said rods being secured to the plunger at one end by a loose connection adapting said rod for lateral movement with respect to the plunger and the other rod for assembling purposes.

17. In a carburetor a structure embodying a fuel nozzle, a piston above and a plunger below and spaced from the nozzle, and rods connecting the piston and plunger, one of said rods being secured by one of its ends with a loose connection to the plunger adapting said rod for lateral movement with respect to the plunger and the other rod, and said rods being secured by one of their ends with a loose connection to said piston adapting said piston for free edgewise movement laterally with respect to said rods.

18. In a carburetor, a mixing chamber, an open ended throat tube in the chamber, a fuel nozzle discharging into said tube, an air passage for atomizing fuel from the nozzle, said air passage also having direct communication with said chamber, a sleeve slidable upon and lengthwise of said tube, one end of the sleeve constituting a valve seat, a piston movable in the chamber and influenced in its operation by engine suction, said piston adapted to co-operate with said valve seat to close the direct communication between the air passage and said chamber, means operatively connected with said piston for metering fuel into said tube, a plunger responsive in its operation to the movement of the piston for forcing fuel into the nozzle, and means for raising the said sleeve with respect to said tube for raising said valve seat and for positively raising said piston.

19. In a carburetor a fuel nozzle, having an inlet opening, valve seat members seated in said opening and having alined openings therethrough to form annular valve seats, said openings at the valve seats being of different diameters, a tapering metering valve member passing through said openings and co-operating with said seats, and means responsive in its operation to engine suction for controlling the movement of said valve member with respect to said seats, the last said means also operable to force fuel through said openings and into said nozzle.

20. In a carburetor a fuel nozzle, having an inlet opening, valve seat members seated in said opening and having alined openings therethrough to form annular valve seats, said openings at the valve seats being of different diameters, a tapering metering valve member passing through said openings and co-operating with said seats, means responsive in its operation to engine suction for controlling the movement of said valve member with respect to said seats, the last said means also operable to force fuel through said openings and into said nozzle, there being a chamber in said members communicating with said open-

ings between said seats, an annular chamber in said members communicating with the first said chamber, and means for supplying fuel through said chambers to augment the supply of fuel discharged past said metering valve and into the nozzle. 5

21. In a carburetor, a fuel nozzle, means for supplying fuel to the nozzle, a metering valve for controlling the said supply, a mixing chamber, an air supply passage having direct communication with said chamber above the nozzle, means for directing a portion of the air from said passage across the nozzle to atomize the fuel therefrom into said chamber, a piston in the chamber controlled in its operation by engine suction, a connection between said piston and said valve whereby the operation of the valve will be responsive to the movement of the piston, said piston also serving as a valve to control the direct connection between the air passage and said chamber, and means controllable at will and movable into and out of contact with said piston for locking said piston against movement in either direction. 10 15 20 25

22. In a carburetor, a fuel nozzle, means for supplying fuel to the nozzle, a metering valve for controlling the supply of fuel to the nozzle, an air supply passage for directing air across the nozzle to atomize the fuel therefrom, a fuel mixing chamber, a piston operating in said chamber and controlled in its operation by engine suction, a connection between said piston and said metering valve whereby the operation of the valve will be controlled by the movement of said piston, means also responsive in its operation to engine suction and operating to augment the supply of fuel to the nozzle past said metering valve, and means controllable at will and individual to the piston and the last said means and respectively movable into and out of engagement therewith, for maintaining them against movement in either direction. 30 35 40 45

23. In a carburetor, a fuel nozzle, means for supplying fuel to the nozzle, a metering valve for controlling the supply of fuel to the nozzle, an air supply passage for directing air across the nozzle to atomize the fuel therefrom, a fuel mixing chamber, a piston operating in said chamber and controlled in its operation by engine suction, a connection between said piston and said metering valve whereby the operation of the valve will be controlled by the movement of said piston, a valve to augment the supply of fuel to the nozzle past the metering valve, means embodying a piston responsive in its operation to engine suction and operating to open the last said valve, means embodying locking elements individual to said pistons for locking them against operation by engine suction, and means for controlling said locking elements at will. 50 55 60
